UNITED STATES PATENT OFFICE.

EMERY W. FANCHER, OF CANTON, CONNECTICUT.

SIDE-BAR WAGON.

SPECIFICATION forming part of Letters Patent No. 251,199, dated December 20, 1881.

Application filed October 7, 1881. (No model.)

To all whom it may concern:

Be it known that I, EMERY W. FANCHER, of Canton, in the county of Hartford and State of Connecticut, have invented a certain new and useful Improvement in Side-Bar Wagons, of which the following is a description, reference being had to the accompanying drawings, where—

Figure 1 is a bottom view of a wagon-box and so much of the appurtenant gear as involves the application of my improvement. Fig. 2 is a view of said gear in cross-section on plane $\alpha\alpha$. Fig. 3 is a detail view of arm and pin.

15 The improvement is in that class of wagons known as "side-bar" wagons, the practical advantages of which are such that they have become firmly fixed in popular favor; and it is the object of my improvement to retain all the 20 present advantages incident to the use of the side bars, and to add thereto a set of springs, which shall give the wagon great additional elasticity, and at the same time be particularly adapted for attachment to the side bars.

25 The letter a denotes a wagon-box; b , side bars, which may be attached to the running-gear by the springs $c c$.

The letters $d d d d$ each denote a coil-spring, with its outer end pivotally attached to the

side bar and with its inner end formed into a 30 square (or many-sided) socket, through which runs the square pin e , provided with the arm e' , which lies flatly on a cross-brace on the bottom of the wagon-box, the purpose of the arm e' being to prevent the rotation of the pin 35 e , and thereby get the action of the coil-spring.

The letter e'' denotes an arm similar to e' , but removable from the pin e , and provided with a square socket to fit on the square end of same. The two arms $e' e''$ are screwed fast 40 to the cross-brace on the bottom of the wagon-box. The cross-brace is mortised out for the reception of the coil of the spring.

It is the action of coil-springs in connection with side bars that I desire to attain, and my 45 claim is not intended to include other springs or end attachments.

I claim as my invention—

In combination, the wagon-body a , the square pins e , fixedly attached thereto, the side bars 50 b , and the springs $d d d d$, coiled at one end around the pins e and pivoted at the other end to the side bars, all substantially as described.

EMERY W. FANCHER.
